UNITED STATES PATENT OFFICE

MARCUS ADLER, OF CHICAGO, AND JOSEPH C. JANOSIK, OF CICERO, ILLINOIS

COMBINATION VEST AND SUSPENDERS

Application filed November 3, 1932. Serial No. 640,988.

This invention relates to clothing and will be described as incorporated in a combination vest and suspenders. This application is in part a continuation of our pending application Ser. No. 524,464 filed March 23, 1931.

An object of this invention is the provision of an improved vest and suspender combination so designed and constructed that distortion of the vest front is avoided by reason of proper distribution of stresses from the suspender straps to the front and shoulder portions of the vest above the pockets.

A further object is the provision of such a combination in which stress is applied to a swinging pocket at a point substantially spaced from the point of attachment of the swinging pocket to the garment to permit a distribution of the stresses across the width of the pocket and uniform application of stress to the front and shoulder portions of the vest above the pocket to avoid distortion of the vest front.

A further object is the provision of such a garment including a lining member providing a lateral reinforcement between the suspender straps at their point of attachment to the swinging pocket and other reinforcement means for sustaining a portion of the strain transmitted to the garment by the suspender straps.

Other objects and advantages of the invention herein illustrated and described will become apparent from the following detail description of the accompanying drawing.

On the drawing:

Figure 1 is a top plan view of a vest and suspender combination incorporating our invention, illustrated as when lying flat on a table, portions of the front of the garment being broken away to more clearly disclose the construction of the back.

Figure 2 is a fragmentary portion of one side of the front with a part broken away to better illustrate the interior.

Figure 3 is a fragmentary rear view of that shown in Figure 2, with a portion broken away to better illustrate the interior of the garment.

Figure 4 is a vertical section through a

portion of the vest, taken on substantially the line IV-IV of Figure 2 and

Figure 5 is a fragmentary section similar to Figure 4 but of a somewhat modified construction.

55

As shown on the drawing:

The garment illustrated in the drawing comprises a vest front consisting of two side portions 3 and 4 which taper at their upper ends to form shoulder portions 5 and 6 which are joined respectively at 7 and 8 to the upper back and neck portion 9. The edges 11 and 12 of the front portions 3 and 4 respectively are secured to the lateral edges of the lower back portion 13 for holding the edges 11 and 12 in proper position on the wearer.

For the purpose of holding the shoulder portions and back in position, there are provided rearwardly extending suspender straps 14 and 15, fixed to the shoulder portions and to the upper back portion 9. The straps 14 and 15 are preferably crossed at 16 and securely stitched together. The straps are also stitched to the lower back portion 13 as indicated at 17. The lower ends of these straps are formed into suspender tabs 18 and 19 adapted to be releasably attached to buttons on the rear of the trousers.

The vest is preferably provided with a plurality of superposed pockets on each side of the front, the lower pockets as shown are of the patch type and the upper pockets are of the swinging type suspended from the upper edge. In Figure 2 a portion of the front cloth or suiting material 21 is broken away together with the lower patch pocket 22 to better illustrate the lining 23 and the lower portion of the upper or swinging pocket 24.

The swinging pocket 24 is attached at 25 and 26 adjacent its upper end to the suiting material 21 and to the reinforcing element 27 illustrated in Figure 4. Spaced suspender straps 28 extend from adjacent the lower edge of the vest to a position overlapping the lower edge of the pocket 24 adjacent the upper edge of the patch pocket 22, and securely sewn in position as illustrated at 29 and 31, the stitching passing through the pocket 24, the suspender strap 28 and a folded portion of the lining 23, such folded portion 32 forming a

80

90

95

100

reinforcement extending laterally between the suspender straps 28 as best illustrated in Figure 3.

By this construction the inner lining 23 5 serves to restrain excessive lateral movement of the straps 28 but permits a limited degree of movement without materially communicating distortion to the front of the vest. As the straps 28 transmit stress to the free 10 lower edge of the pocket 24, each strap being attached adjacent a lower corner of a substantially rectangular piece of cloth forming the pocket 24, distributes stress across the entire upper edge of the pocket. 15 This stress, being substantially uniformly distributed even though the straps 28 sway laterally a limited amount as permitted by the reinforcing 32 of the lining, is therefore applied substantially uniformly to a wide 20 strip of the front and shoulder portions above the swinging pocket, in a manner to very effectively and snugly hold the vest in position without transmitting distortion to the front material of the vest.

25 The form of this invention illustrated in Figure 5, is similar to that above described, but is provided with an additional reinforcement 36 which is a continuation of the suspender strap 28. The reinforcement 36 is secured at its upper ends to the reinforcement 27 and to the front material of the vest at the corner of the pocket by stitching at 38 and 41. The reinforcement 36 and the strap 28, being respectively upper and lower ends 30 of the same element are anchored by stitching 42 to the front material 21 and to the extreme corner of the lower pocket 22. This form of the invention provides a more rigid 35 garment and may be preferred for certain 40 purposes.

From the foregoing description it will be appreciated by those skilled in the art that this invention is susceptible of various forms and modifications without departing from 45 the principle of the invention, accordingly we desire that the patent to be granted hereon shall not be limited in any manner except as required by the prior art.

We claim as our invention:

50 1. In a vest and suspender combination, a vest front including shoulder portions, a swinging pocket secured to the vest front adjacent the upper edge of the pocket, suspender straps extending below said pocket and secured to the lower free edge of the 55 pocket to uniformly distribute stress across the front and shoulder portions of the vest above said pocket without distorting the front of the vest.

60 2. In a vest and suspender combination, a vest front including shoulder portions, a swinging pocket secured to the vest front adjacent the upper edge of the pocket, suspender straps extending below said pocket 65 and secured to the lower free edge of the

pocket to uniformly distribute stress across the front and shoulder portion of the vest above said pocket without distorting the front of the vest and reinforcing means secured to said suspender straps and extending upwardly along the rear side of said swinging pocket to said shoulder portion. 70

3. In a vest and suspender combination, a vest front including shoulder portions, a swinging pocket secured to the vest front adjacent the upper edge of the pocket, suspender straps extending below said pocket and secured to the lower free edge of the pocket to uniformly distribute stress across the front and shoulder portion of the vest above said pocket without distorting the front of the vest, said suspender straps also extending adjacent the opposite edges of said swinging pocket and secured to the upper corners of the pocket to reinforce the swinging pocket. 80 85

4. In a vest and suspender combination, a vest front including shoulder portions, superposed pockets on each side portion of the front, the upper one being a swinging pocket secured adjacent its upper edge to the vest front, suspender straps extending from below the pocket upwardly and securely stitched to the lower free edge of the upper pocket to uniformly distribute stress to the front and shoulder portions of the vest without distorting the vest front and reinforcing means secured to said suspender straps and extending upwardly along the rear side of said swinging pocket to said shoulder portion. 90 95

5. In a vest and suspender combination, a vest front including shoulder portions, superposed pockets on each side portion of the front, the upper one being a swinging pocket secured adjacent its upper edge to the vest front, suspender straps extending from below the pocket upwardly and securely stitched to the lower free edge of the upper pocket to uniformly distribute stress to the front and shoulder portions of the vest without distorting the vest front, said suspender straps also extending adjacent the opposite edges of said swinging pocket and secured to the upper corners of the pocket to reinforce the swinging pocket. 100 105 110

6. In a vest and suspender combination, an upper back and shoulder portion, rearwardly extending suspender means operably secured to the shoulder portions, a vest front including superposed pockets, the upper one being a swinging pocket suspended by its upper edge from the vest front, a reinforcing member extending from the point of attachment of the upper edge of the swinging pocket, to the shoulder portion, suspender straps secured to the lower free edge of the swinging pocket for distributing stress uniformly across the pocket and across the front and shoulder portion above the pocket. 115 120 125

7. In a vest and suspender combination, an upper back and shoulder portions, rearward- 130

ly extending suspender means operably secured to the shoulder portions, a vest front including superposed pockets, the upper one being a swinging pocket suspended by its upper edge from the vest front, a reinforcing member extending from the point of attachment of the upper edge of the swinging pocket, to the shoulder portion, suspender straps secured to the lower free edge of the swinging pocket for distributing stress uniformly across the pocket and across the front and shoulder portion above the pocket a lining for the vest front disposed rearwardly of said pocket and including a portion folded over the upper end of said suspender straps and secured thereto for providing a reinforcement between the upper ends of the straps.

8. In a vest and suspender combination, an upper back and shoulder portions, rearwardly extending suspender means operably secured to the shoulder portions, a vest front including superposed pockets, the upper one being a swinging pocket suspended by its upper edge from the vest front, a reinforcing member extending from the point of attachment of the upper edge of the swinging pocket, to the shoulder portion, suspender straps secured to the lower free edge of the swinging pocket for distributing stress uniformly across the pocket and across the front and shoulder portion above the pocket, a lining for the vest front disposed rearwardly of said pocket and including a folded portion secured to the straps to form a reinforcement therebetween at the point of attachment to the lower edge of the swinging pocket, said straps extending through said lining and being additionally secured to the opposite corners at the upper edge of the swinging pocket.

In testimony whereof, we have hereunto subscribed our names at Chicago, Cook County, Illinois.

MARCUS ADLER.
JOSEPH C. JANOSIK.
